UNITED STATES PATENT OFFICE.

MORRIS SHORE, OF PHILADELPHIA, PENNSYLVANIA, ASSIGNOR TO SANITARY REFRIGERATOR CORPORATION, OF PHILADELPHIA, PENNSYLVANIA, A CORPORATION OF PENNSYLVANIA.

DESIGN FOR A SPIGOT.

Application filed January 21, 1926. Serial No. 16,192. Term of patent 7 years.

To all whom it may concern:

Be it known that I, MORRIS SHORE, a citizen of the United States, residing at Philadelphia, in the county of Philadelphia and State of Pennsylvania, have invented a new, original, and ornamental Design for a Spigot, of which the following is a specification, reference being had to the accompanying drawing, forming a part thereof.

In the accompanying drawing, Fig. 1 is a

front elevation, Fig. 2 is a plan view, and Fig. 3 is a perspective view of a spigot showing my new design.

I claim:

The ornamental design for a spigot as shown.

In testimony whereof I have hereunto set my hand this 13 day of January, 1926.

MORRIS SHORE.
